(57) **CLAIM**

The ornamental design for the apparatus for coupling pressurized water supply to recreational vehicle fresh water fill port as shown and described.

DESCRIPTION

FIG. 1 is a top perspective view of an apparatus for coupling pressurized water supply to recreational vehicle fresh water fill port;

FIG. 2 is a bottom perspective view thereof;

FIG. 3 is a side elevation view thereof;

FIG. 4 is a top plan view thereof; and,

FIG. 5 is a bottom plan view thereof.

The broken lines depict portions of the apparatus for coupling pressurized water supply to recreational vehicle fresh water fill port that form no part of the claim.
